UNITED STATES PATENT OFFICE.

VICTOR BENDER, OF WESTVILLE, ILLINOIS.

AUTOMOBILE NUMBER-PLATE.

1,096,670.

Specification of Letters Patent. Patented May 12, 1914.

Application filed November 19, 1912. Serial No. 732,270.

To all whom it may concern:

Be it known that I, VICTOR BENDER, a citizen of the United States, residing at Westville, in the county of Vermilion and State of Illinois, have invented new and useful Improvements in Automobile Number-Plates, of which the following is a specification.

This invention relates to indicators for 10 automobiles or like carriers, which are licensed to travel in a certain jurisdiction; and has for an object to provide means whereby the license number will be clearly visible at all times.

Another object of the invention is to provide an adjustable tape of differently distinguished display portions, which are adapted to be singly presented behind the stencil or license display surface of the indicator and means for positively preventing the accidental slipping of the tape from its adjusted position.

With these and other objects in view, the invention consists of certain novel features 25 of construction, combination and arrangement of parts, as will be hereinafter described and claimed.

In the accompanying drawings: Figure 1 is a perspective view of the indicator; Fig. 30 2 is a transverse section therethrough; Fig. 3 is a section on line 3—3 of Fig. 1; and Fig. 4 is a section on line 4—4 of Fig. 2. Fig. 5 is a section on line 5—5 of Fig. 3.

The indicator comprises a receptacle 1 35 which may be arranged on any portion of the carrier from which the license number is to be displayed, and as shown the receptacle is provided with a wall 2 having stencil numbers 3 or license indicating portions. The receptacle is divided into separate and 40 distinct compartments 4 and 5, through the medium of an intermediate transparent panel 6 of glass, preferably. Illuminating means, such as an acetylene gas burner 7, is arranged in the compartment 5, so that when lighted a proper illumination of the display surface of the signal will be made. The lower wall of the compartment 5 is provided with one or more ventilating passages 8,

50 while the upper wall of said compartment is provided with one or more ventilators 9, so that the compartment will be open to the outside air. The lower wall of the compartment 4 is provided with ventilating passages 10 while the upper wall of said compartment is provided with similar ventilat-

ing passages 11. The passages 10 and 11 also open to the outside air so that the compartment 4 may be maintained in a cool condition at all times.

With a view to illuminate the display surface of the signal by a prescribed color, I provide a tape 12, which is provided with a red or suitable colored translucent portion 13 and a white portion 14. A roller 15 is mounted in the side walls of the compartment 4 at a point behind the plane of the display surface of the signal and as illustrated said roller has one end of the tape 12 wound thereon. The tape is adapted to be 60 adjusted behind the display portion of the signal and as shown the upper end of the tape is wound around an adjusting roller 16. The roller 15 is adapted, under the action of its spring 17, to revolve in a direction to 65 wind the tape 12 around the roller when the roller 16 is released. The roller 16 is provided with an end trunnion 18 having a rectangular extremity 19 which is extended 70 beyond the end of the receptacle 1. The rectangular portion has slidably arranged thereon a manipulating wheel 20 whose bore 21 conforms to the configuration of the rectangular portion 19 so that said roller 16 may 75 be revolved when the wheel is manipulated. The receptacle 1 has a squared socket 22, 80 which is adapted to receive a correspondingly formed portion 23 of the manipulating wheel. A spring 24 on the receptacle 1 is terminally connected, as at 25, with the 85 portion 23 so as to normally hold the same in the socket 22. In this manner, the roller 16 will be held against revolving under the action of the lower spring roller 15. The rectangular portion 19 is provided with a 90 stop 26, which is disposed in the direct path of adjustment of the wheel 20, and designed to engage against one side of the wheel to prevent the displacement thereof. When the wheel is adjusted against the stop, the 95 portion 23 will be retracted from the socket 22. The roller 16 may then be revolved to permit the tape to pass from the roller 16 to the roller 15 or vice versa.

Now that the details of construction of 105 the device are clearly described, it is seen that in the day-light, the tape 12 is adjusted so as to cause the white portion thereof to lie immediately behind the stencil or display portion of the signal. At night, the 110 tape 12 is adjusted so as to bring the red signaling portion behind the license bear-

ing display surface of the signal, as is evident.

From the foregoing description, taken in connection with the accompanying drawings, 5 the construction and operation of the invention will be readily understood without requiring a more extended explanation.

Having thus described my invention, what I claim is:—

- 10 A signal comprising a casing having a stencil signaling surface, a tape adjustable behind said surface and having a colored portion, an upper roller having a rectangular portion, a lower spring tension roller, the
- 15 said first and second named rollers having the opposite ends of the tape wound there-

around, the casing having a rectangular socket, a manipulating member adapted for sliding adjustment on the rectangular portion of the first roller and adapted to revolve with the roller and provided with a squared portion adapted for locking engagement in the socket, and means bearing against the member to hold said squared portion thereof normally in said socket.

In testimony whereof I affix my signature in presence of two witnesses.

VICTOR BENDER.
